UNITED STATES PATENT OFFICE.

MICHAEL KOHUT, OF ELMHURST, NEW YORK, ASSIGNOR TO S. H. POMEROY COMPANY, INC., OF NEW YORK, N. Y., A CORPORATION OF NEW YORK.

METAL WINDOW.

Application filed November 3, 1927. Serial No. 230,754.

This invention relates to hollow metal window frames of the construction shown and described in an application for Letters Patent of the United States of Alphonsus 5 Fien, Serial No. 230,755, filed concurrently herewith, and is particularly concerned with the strengthening of the frame at each upper corner where the jamb and the head of the frame are secured together, the purpose being 10 to provide such construction that the frame shall be capable of resisting breakage or distortion in the rough handling to which such frames are sometimes subjected in transportation and in erection on the job. 15 The invention is also concerned with the support of the sash pulleys, the housing of the pulleys at each side being of such character as to permit the use of pulleys of substantial diameter, so as to carry the chains 20 properly and to permit each chain to be carried in the recess of the pulley stile, at one side of the pulley, and to be carried centrally over the weight in the hollow jamb or weight box.

25 The pulley housing is so constructed as to serve the purpose of strengthening the frame at the corners as above mentioned. The features of construction in which the present invention is embodied are illustrated 30 in the drawings described in the specification of the application above mentioned Serial No. 230,755, but, being the subject of a separate and independent invention, are also shown and described herein, like reference 35 characters being employed, as far as possible, to indicate like parts in the two cases, for convenience in enabling the relation of the two inventions to be understood. In the accompanying drawings, in which the present 40 invention is illustrated;

Figure 1 is a view in front elevation, as seen from the inside of the window, of the upper left-hand portion of a window frame which embodies the invention, portions of 45 the jamb and of the frame head being shown as well as a portion of one of the window sashes, the jamb and the head being partly broken out and shown in vertical section.

Figure 2 is a view of the same as seen 50 from above, the cap of the head being removed and a portion of the inturned flange of the head, at the outside of the window, being broken out.

Figure 3 is a view in sectional elevation on 55 the plane indicated by the broken line 3-3

of Figure 1 looking in the direction of the arrows.

Figure 4 is a view in horizontal section on the plane indicated by the broken line 4-4 of Figure 1 looking upward.

Figure 5 is a detail view in section on the plane indicated by the broken line 5-5 of Figure 4.

Figure 6 is a detail view in section on the plane indicated by the broken line 6-6 of Figures 2 and 3.

Figure 7 is a top view of the reinforcing plate and pulley housing.

Figure 8 is a perspective view of the reinforcing plate applied to the jamb at its upper end.

The complete window frame includes a head, a sill and two jambs which are identical except for reversal. Each jamb *a* may be made of a single sheet of metal, formed to suit the window opening in the wall and to receive within it the counter-balance weights, not shown, for the upper and lower sashes, the upper sash being shown in part in Figure 1.

The edge portions of the sheet of metal which forms the jamb are bent toward each other and again toward the back of the jamb to form jamb members *a*¹ and *a*², the edges being again bent toward each other, in a plane transverse to the plane of the window, to form flanges as at *a*³ and *a*⁴, which are spaced apart throughout the vertical height of the frame. The jamb thus formed is stiffened and strengthened and its edge portions maintained in proper spaced relation by heavy metal reinforcing plates as more particularly described in said application Serial No. 230,755. The upper jamb reinforcing plate *b*, which is shaped to fit against the jamb portions *a*¹ and *a*² on the inside, to maintain the edge portions of the jamb against relative displacement, is formed at its upper edge with tongues *b*¹, *b*² and *b*³ for connection with the head of the frame as hereinafter described, being thereby held from relative displacement in a vertical direction.

The pulley stile, the upper section *e* of which is alone shown in the drawings, is 105 formed to fit between the members *a*¹ and *a*² of the jamb and is bent to form projecting vertical rails which, between themselves and with portions *a*¹ and *a*² of the jamb, form the grooves to receive the flanges of the up-

per sash *i* and the counterbalance chains, one of which is shown at *l* in Figure 1. Each pulley *o* is of such size and is so disposed and supported, as hereinafter described, that 5 the portion of the chain *l* which lies in the groove of the pulley stile, is tangent to the pulley in the plane thereof, while the other portion of the chain, which is connected at its end to the sash, is also tangent to the 10 pulley and in the plane thereof.

The soffit *m*¹ of the head *m* is grooved as at *m*² to receive the flanges across the top of the upper sash *i*, and within the head, extending from the inner face to the outer 15 face, is a heavy metal reinforcing plate *n*, which is formed with slots *n*¹, *n*² and *n*³ and is formed at its inner edge with a downwardly bent flange, as at *n*⁴, to bear against the inner face of the head and at its outer 20 edge with an upwardly turned flange, as at *n*⁵, to bear against the outer face of the jamb. The tongues *b*¹, *b*² and *b*³ of the upper reinforcing plate *b* pass up through a slot at *m*³, in the soffit *m*¹ and past the 25 end of the soffit through the slots *n*¹, *n*², and *n*³ in the reinforcing plate *n* and are bent over upon the reinforcing plate *n* securing it rigidly to the frame head. A tongue *a*⁵ of the jamb is also passed up 30 through the slot *m*³ and is bent over in a direction opposite to that of the tongue *b*¹. The jamb is also formed with tongues *a*⁶ and *a*⁷ which are passed up through slots *m*⁶ and *m*⁷ in the inwardly turned edge of 35 the soffit *m*¹ and are bent over toward each other. At its outer face the jamb is formed with a tongue *a*⁸ which is bent over upon the edge of an extended tongue *m*⁸ of the soffit. At its inner face the soffit is also 40 formed with an extended tongue *m*⁹, the upper edge of which is bent over upon itself as at *m*¹⁰, and is cut out to form two shoulders *m*¹¹ and *m*¹². The inner wall of the jamb is bent over upon the extended tongue 45 *m*⁹ of the soffit and has a tongue *a*⁹ which is bent down between the shoulders *m*¹¹ and *m*¹². In this manner the jamb is rigidly secured to the frame head to prevent relative displacement in a vertical direction and 50 at the same time is secured rigidly to the frame head to prevent relative displacement in a horizontal direction.

Each pulley *o* is mounted to turn on a spindle *o*¹, which is held in downwardly 55 extended ears *o*² of a guard housing *o*³. The latter is conveniently secured in place on the reinforcing plate *n* by lugs *o*⁴ of the housing *o*³ which are passed down through slots, indicated at *n*⁶ in the reinforcing plate 60 *n*. It will be understood that the guard housing and the pulleys are set somewhat obliquely with respect to the plane of the window so as to bring the parts of the chains properly in line with the sashes and the 65 counter-balance weights.

It will be seen that the provision of this heavy metal reinforcing plate, which is fitted closely between the front and rear faces of the frame head and against the upper end of the jamb, and is rigidly secured to the 70 jamb and to the upper reinforcing plate of the jamb, contributes materially to the strength and rigidity of the frame at the corner and holds it against distortion, while at the same time it provides a convenient 75 support for the sash pulleys.

Various changes in detail of construction and arrangement can be made to suit the conditions of use, and it will be understood that except as set forth in the accompanying 80 claims the invention is not restricted to the particular construction and arrangement shown and described herein.

I claim as my invention:

1. In a metal window the combination of 85 a sheet metal jamb, a sheet metal frame head, means to secure together the jamb and the frame head, a horizontal heavy metal reinforcing plate fitted within the frame head at its end and extended across the jamb near 90 its upper end and fitted into the same, and means to secure the jamb to said plate.

2. In a metal window the combination of 95 a sheet metal jamb, a sheet metal frame head, means to secure together the jamb and the frame head, a heavy metal reinforcing plate fitted within the frame head at its end, a sash pulley, and means to support the sash 100 pulley on the reinforcing plate.

3. In a metal window the combination of 100 a sheet metal jamb, a sheet metal frame head, means to secure together the jamb and the frame head, a heavy metal reinforcing plate fitted within the frame head at its end, a sash pulley, and a pulley housing supporting 105 the sash pulley and secured to the reinforcing plate.

4. In a metal window the combination of 110 a sheet metal jamb, a sheet metal frame head, a heavy metal reinforcing plate fitted within the frame head at its end and slotted, and a heavy metal reinforcing plate fitted within the jamb at its upper end and formed with a tongue to enter a slot of the first mentioned reinforcing plate.

5. In a metal window the combination of 115 a sheet metal jamb, a sheet metal frame head, a heavy metal reinforcing plate fitted within the frame head at its end and slotted, and a heavy metal reinforcing plate fitted within the jamb at its upper end, and formed with a tongue to enter a slot of the first mentioned reinforcing plate, the tongue of the last mentioned reinforcing plate being bent over against the first mentioned reinforcing plate. 120

6. In a metal window the combination of 125 a sheet metal jamb, a slotted sheet metal frame head, and a slotted heavy metal reinforcing plate fitted within the frame head at its end, the jamb being formed with a tongue 130

to enter the slots of the frame head and the reinforcing plate.

7. In a metal window the combination of a sheet metal jamb, a slotted sheet metal frame head, and a slotted heavy metal reinforcing plate fitted within the frame head at its end, the jamb being formed with a tongue to enter the slots of the frame head and the reinforcing plate and said tongue being bent over against the reinforcing plate.

8. In a metal window the combination of a sheet metal jamb, a slotted sheet metal frame head, a slotted heavy metal reinforcing plate fitted within the frame head at its end, and a heavy metal reinforcing plate

fitted within the jamb at its upper end and formed with a tongue to enter the slots of the frame head and the first mentioned reinforcing plate.

9. In a metal window the combination of a sheet metal jamb, a sheet metal frame head, a heavy metal reinforcing plate fitted within the frame head at its end and slotted, a pulley housing formed with ears extending through the slot of the reinforcing plate, and a sash pulley supported by said ears.

This specification signed this 1st day of November A. D. 1927.

MICHAEL KOHUT.
